UNITED STATES PATENT OFFICE.

EVA KITTLEMAN, OF COUNCIL BLUFFS, IOWA.

DESIGN FOR A DOLL.

Application filed January 16, 1922. Serial No. 220. Term of patent 3½ years.

To all whom it may concern:

Be it known that I, EVA KITTLEMAN, a citizen of the United States, residing at Council Bluffs, in the county of Pottawattamie and State of Iowa, have invented a new, original, and ornamental Design for Dolls, of which the following is a specification, reference being had to the accompanying drawings, forming part thereof.

Figures 1 and 2 are views of the opposite faces of a doll, showing my new design; and Figure 3 is a side view of the doll.

I claim:

The ornamental design for a doll, as shown.

EVA KITTLEMAN.
